Primary Examiner — Khawaja Anwar*Assistant Examiner* — Mojtaba Tehrani(74) *Attorney, Agent, or Firm* — Dossey & Jones, PLLC;
Phillip Black; James P. Dossey(57) **CLAIM**

The ornamental design for a handle cut-out, as shown and described.

DESCRIPTION

FIG. 1 is a rear top-left perspective view of a handle cut-out, showing my new design;

FIG. 2 is a rear top-right perspective view thereof;

FIG. 3 is a front bottom-right perspective view thereof;

FIG. 4 is a front bottom-left perspective view thereof;

FIG. 5 is a right side view thereof; and,

FIG. 6 is a left side view thereof.

The broken lines in the drawings disclose unclaimed portion of the handle only and form no part of the claimed design.

1 Claim, 3 Drawing Sheets(56)
